(57) **CLAIM**

The ornamental design for a slider for a user interface for an image processing machine, as shown and described.

DESCRIPTION

FIG. 1 is a front view of a slider for a user interface for an image processing machine of the present invention; FIG. 2 is a front view of a second embodiment thereof; FIG. 3 is a front view of a third embodiment thereof; FIG. 4 is a front view of a fourth embodiment thereof; and, FIG. 5 is a front view of a fifth embodiment thereof. The broken line drawings of a user interface in all views and the arrow in FIG. 2 is for illustrative purposes only and form no part of the claimed design.
